(57) **CLAIM**

The ornamental design for a shoe, as shown and described.

DESCRIPTION

FIG. 1 is a bottom perspective view of a shoe in accordance with my new design;

FIG. 2 is a bottom view thereof;

FIG. 3 is a top view thereof;

FIG. 4 is a left side view thereof;

FIG. 5 is a right side view thereof;

FIG. 6 is a front view thereof;

FIG. 7 is a rear view thereof; and,

FIG. 8 is an enlarged perspective view of the area labeled “8” in FIG. 1.

The shoe upper shown in broken lines in FIGS. 1–7 is for environmental purposes only and forms no part of the claimed design. The broken lines shown in each arch area of FIGS. 1 and 2 represent boundaries of the design with the lines themselves and the areas within them forming no part of the claim.
